UNITED STATES PATENT OFFICE.

GREEN C. LANCASTER, OF PARMA, MISSOURI.

CHAIR ATTACHMENT FOR TABLES.

1,303,921.

Specification of Letters Patent. Patented May 20, 1919.

Application filed September 14, 1915, Serial No. 50,659. Renewed March 6, 1919. Serial No. 281,077.

To all whom it may concern:

Be it known that I, GREEN C. LANCASTER, a citizen of the United States, residing at Parma, in the county of New Madrid and 5 State of Missouri, have invented certain new and useful Improvements in Chair Attachments for Tables, of which the following is a specification.

My invention relates to furniture and 10 more particularly to chair attachments for tables.

The invention has for its primary object the provision of a suitable chair attachment for tables which will allow the transportation 15 of chairs and a table from place occupying the smallest possible space.

Another object of the invention is to provide a device of the character before mentioned in which the chairs are permanently, 20 if so desired, associated with a table and readily foldable under the table when unoccupied. The invention is particularly adapted for use in restaurants and on ship board, suitable means being provided 25 whereby the table and all of the chairs associated therewith may be readily moved from place to place.

With the above and other objects in view my invention resides preferably in the construction, combination, and arrangement of 30 parts as hereinafter set forth in the specification as illustrated in the accompanying drawings, in which—

Figure 1 is a top plan view of a table embodying improvements of my invention, portions of the same being broken away,

Fig. 2 is an enlarged and perspective view of one end of the table showing one of the chairs associated therewith and in position 40 to be occupied.

Similar reference characters designate similar parts throughout the various views of the drawings.

In the drawings I have provided a table 45 having usual top board 1, said table being provided with four legs designated 2 adjacent the corners thereof, the space between said legs being closed by longitudinally and transversely extending walls 3, said walls

50 being provided at predetermined points with openings, said openings being closed by doors 4, hinged as at 5. Vertical posts 6 serve as jambs for the several doors, all of said doors being practically identical in construction and for this reason I will describe 55 but one of them. As shown to advantage in

Fig. 2, the door 4 is provided with a suitable latch or the like 7, and a chair of any suitable type designated 8 is carried permanently by said door, the chair legs 9 are provided with casters 10 to facilitate the movement of the chairs into and out of position for occupation. Suitable rollers 11 are provided on the table legs and at intermediate points beneath the table to facilitate movement of the 65 table from place to place.

In Fig. 1, a chair is shown in the outer position ready for occupation. It will be understood, of course, that while chairs have been shown, any suitable seat may be provided, and in lunch rooms or restaurants, stools may be provided. This will save a great deal of space, since, when the chair is unoccupied, it may be moved under the table and allow a wider passage than would ordinarily exist between the tables. It will be further noted that by having the back and front portions of the chair extending at right angles to the door, the chair will be in position to allow the occupant to be easily seated thereon. Furthermore, the particular arrangement of the chair causes the proper spacing of the occupants seated around the table. It is of course obvious that the occupant would desire to be squarely in front of 85 the table and for this reason would pull the chair to the position illustrated in Fig. 2 and also in Fig. 1 where the one door is shown in an open position. This of course, would cause the doors to be extending exactly at right 90 angles to the supporting wall, when in an open position and in this way the various occupants would not crowd each other but would be properly spaced apart. Any suitable means, not shown, may be provided for 95 connecting the chairs to their respective doors and it is to be understood that while I have shown and described the invention as embodying a specific structure, such as substitution of the chairs with stools or the like 100 and modifications of the doors for application to different types of tables without departing from the spirit and scope of the invention.

I claim—

105
In a chair attachment for tables, the combination of a top board, supporting legs carried by said top board, walls connected to said top board and said legs, said walls having openings formed therethrough, doors 110 pivotally mounted upon the walls for normally closing the openings therein, a chair

having a back thereon fixedly connected to each door, the front portion of said chair extending at right angles to the surface of said door, thus causing the chair to be facing said top board when the door is swung to an open position at right angles to its supporting wall.

In testimony whereof I affix my signature in presence of two witnesses.

GREEN C. LANCASTER.
